(57) **CLAIM**

The ornamental design for an airbrush makeup compressor cabinet, as shown and described.

DESCRIPTION

FIG. 1 is a side view of an airbrush makeup compressor cabinet showing my new design; the broken lines representing an airbrush form no part of the claimed design;

FIG. 2 is a front perspective view thereof;

FIG. 3 is a rear perspective view thereof;

FIG. 4 is a front view thereof;

FIG. 5 is a rear view thereof;

FIG. 6 is a top view thereof; and,

FIG. 7 is a bottom view thereof.
